UNITED STATES PATENT OFFICE.

EDWARD MAURICE TRIMBLE, OF ROCHESTER, NEW YORK.

CONVERTIBLE CRIB AND COOP.

1,079,675.

Specification of Letters Patent. Patented Nov. 25, 1913.

Application filed February 17, 1913. Serial No. 749,037.

To all whom it may concern:

Be it known that I, EDWARD MAURICE TRIMBLE, a citizen of the United States, and resident of Rochester, in the county of Monroe and State of New York, have invented 5 certain new and useful Improvements in Convertible Cribs and Coops, of which the following is a specification.

This invention relates to folding cribs or 10 beds for infants, of the type in which the end-walls may be folded in such a manner as to permit the side-walls to be brought close together for the purpose of producing a crib of compact form.

15 The object of the invention is to produce a device, of the type in question, which is adapted to perform the double function of a crib and of a coop or inclosure for an infant, the device, when performing the 20 latter function, being so arranged that the infant may stand or walk within it while being confined by walls of a safe height.

To the foregoing end I propose to employ a device having folded walls, and a bottom 25 or mattress-support which may be swung upwardly about one edge into a vertical position between the side-walls, together with means for supporting this bottom at different levels within the walls, 30 whereby it may be held either in a raised position, adapting the device for use as a crib, or in a lower position, adapting it for use as a coop or inclosure.

In the drawings:—Figure 1 is a perspective view of a combined crib and coop embodying the present invention, with the parts in position for use as a coop; Fig. 2 is a plan-view of the same, with the parts in position for use as a crib; Fig. 3 is a partial vertical-section near one end of the device, on a larger scale than the preceding figures; and Fig. 4 is a plan-view, showing the device in folded position.

The illustrated embodiment of the invention is provided with side-walls 5 and 6, which comprise frameworks closed by panels 7 of wire-netting. The side-wall 5 has narrow lateral extensions 8 at its ends, to which the end-walls are attached, these end-walls 50 each comprising two sections 9 and 10, of which the section 9 is fastened, by hinges 11, to the extensions 8. The sections 9 and 10 are likewise fastened together by hinges 12, and the sections 10 are fastened, by 55 hinges 13, to the side-wall 6.

The bottom of the device comprises a rec-

tangular frame 14, upon which wire-netting or other fabric 15 is stretched to form a floor, or to provide a support for a mattress 19. To the frame 14 of the bottom are 60 fixed two pivots 16 which may rest in sockets 17 fixed within the side-extensions 8 near the bottom thereof. These parts are used when the device is to be used as a coop, and in this case the opposite side of the bottom 65 is supported by resting upon a flange 18 fixed longitudinally within the side-wall 6 near the bottom thereof. When the bottom of the device is so supported it is in its lowermost position, thus providing a coop 70 having walls of sufficient height to safely confine an infant. In this position of the device a mattress may be used or not, as may be considered desirable.

When the device is to be used as a crib 75 the bottom is raised to the position shown in dotted lines in Fig. 3, and is there supported upon pins 20 which are introduced for this purpose in sockets provided in the sides 5 and 6, as shown in Figs. 2 and 3, 80 the pins being freely removable from the sockets when it is desired to lower the bottom. In its raised position the bottom affords a mattress-support at a convenient height, while the upper portions of the side- and end-walls perform the function of the walls usually employed in a crib.

When the device is to be folded the pins 20 are removed and the bottom is lowered to permit the pivots to rest in the sockets 90 17, and the bottom is then swung, about these pivots, to the vertical position shown in full lines in Fig. 4, and in dotted lines in Fig. 3. The end-walls may then be folded inwardly, and the side-wall 6 brought toward the side-wall 5, as shown in Fig. 4, thus substantially diminishing the bulk of 95 the device.

The device may be supported upon the floor in any convenient manner, but it is 100 preferably mounted upon wheels 21, which are journaled between brackets 22 projecting downwardly from opposite sides of the side-walls 5 and 6, as illustrated. Owing to the considerable height of my combined 105 crib and coop, which is necessary to permit it to perform the double function above described, it is not necessary to provide for folding the bottom otherwise than by swinging it upwardly about pivotal points near 110 one edge as described, since in such position the bottom will not project substantially

above the walls, as the walls are of a height substantially equal to the width of the bottom.

I claim:—

- 5 A folding crib having, in combination, a rectangular bottom-member; vertical side-members of a height substantially equal to the width of the bottom-member; end-members connecting the side-members and adapted to fold to bring the side-members toward each other; means, located adjacent the lower edges of the side-members, for supporting the bottom in a lower position, the
- 10

bottom being freely removable, upwardly, from said means, and said means, adjacent one side, being pivotal to permit the bottom to be swung to vertical position when the crib is folded; and means for supporting the bottom, horizontally, in a higher position between the side-members and the end-members.

EDWARD MAURICE TRIMBLE.
